Primary Examiner — Catherine S Posthauer(74) *Attorney, Agent, or Firm* — JCIP; Joseph G. Chu;
Jeremy I. Maynard**CLAIM**

The ornamental design for a lid for a container, as shown and described.

DESCRIPTION

FIG. 1 is a front perspective view of a lid for a container;
FIG. 2 is a rear perspective view of the lid for a container;
FIG. 3 is a front view of the lid for a container;
FIG. 4 is a rear view of the lid for a container;
FIG. 5 is a right side view of the lid for a container;
FIG. 6 is a left side view of the lid for a container;
FIG. 7 is a top view of the lid for a container; and,
FIG. 8 is a bottom view of the lid for a container.
Broken lines depict portions of the lid for a container that
form no part of the claimed design.
